FRANK KNIZEK, OF DOTY, WASHINGTON.

SAW-FILING TOOL.

1,330,042.

Specification of Letters Patent.

Patented Feb. 3, 1920.

Application filed March 31, 1919. Serial No. 286,269.

To all whom it may concern:

Be it known that I, FRANK KNIZEK, a citizen of the United States, residing at Doty, in the county of Lewis and State of Washington, have invented certain new and useful Improvements in Saw-Filing Tools, of which the following is a specification.

This invention relates to saw filing tools and, more especially, to improvements in saw gages and jointers. The object of my invention is the perfecting of devices of this character whereby the teeth of a saw may be more accurately and expeditiously dressed than hitherto.

With these ends in view, the invention consists in the novel construction, arrangement and combination of parts, as will be hereinafter described and claimed.

In the accompanying drawings, Figure 1 is a top plan view of a saw tool embodying my invention; Fig. 2 is a rear elevation; Fig. 3 is a front elevation shown partly in section; Fig. 4 is an underside plan view; Fig. 5 is a central transverse sectional view through the aforesaid views.

The device is formed with a body or frame having a web comprised of a central member 5 and end members 5¹ which are formed integral with two flanges 6 which extend forwardly from the upper ends of said members. Between said flanges and continued into the central member 5 is a recess 7. At the front of the frame and intermediate its height it is provided with longitudinal ribs 8. Ribs 9 are provided at the back of the frame and extend rearwardly from the latter to terminate in a vertical plane in which is located the rear edges of flanges 6 and serving therewith to retain the tool in an upright position when juxtaposed with the blade of a saw.

The portions of the frame members 5 and 5¹ below the ribs 8 and 9 are offset, as at 5² (Fig. 5) forwardly with respect to the parts of the members above said ribs, and terminate in forwardly projecting bracket or stirrup elements 5³ and 5⁴. Secured centrally of its length by screws 10 upon the stirrup 5³ is a longitudinal plate 11 which extends over the other stirrup 5⁴ and is seated adjacent to its ends and at its mid-width upon screws 10¹ extending through the respective stirrups 5⁴.

By regulating the screws 10¹ the plate 11 is curved vertically to an arc of a circle corresponding to that in which the points of the

cutter teeth of a saw are located and is primarily designed to be used as a gage to test such arc, and also serves as a backing, or form, against which is bent a file (shown by broken lines A in Fig. 2) through the instrumentality of a clamping screw 12 extending through a threaded hole in a lug 13 provided at the rear of the frame, as best shown in Figs. 2 and 5.

The plate 11 is disposed to have its front edge 11¹ in a vertical plane with the front edges of the ribs 8 and the width of the plate is such that it will project beyond the plane of the rear edges of the ribs 9 at the back of the frame.

Positioned below each of the flanges 6 are flexible plates 14 extending the entire length of the respective flanges and are secured thereto in proximity to their inner ends by means of screws 15.

16 represents a gage block secured to the frame member 5 in vertically adjusted positions by means of headed screws 17 passing through slots 17¹ provided in the member 5 and engaging in threaded holes provided in lugs 16¹ depending from the block 16.

18 represent screws engaging in threaded holes provided in frame flanges 6 and thence through apertures, such as 14¹, provided in the plates 14. The lower ends of the screws 18 engage against the upper surface 16² of said block and whereby the elevation of the block may be regulated.

In proximity to the outer ends of flanges 6 are provided threaded holes for screws 18¹ whose lower ends impinge the subjacent plates 14 for the purpose of pressing down on the free ends of the plates to curve the same to the arc of the cutting teeth of a saw.

The aforesaid block is provided with a slot 19 which is rectangular in horizontal section, and with the end walls 19¹ sloping outwardly below their juncture with the top face 16² of the block.

20 and 21 represent lock nuts for securing the screws 18¹ and 10¹ respectively.

The operation of the invention is as follows:

A saw is first tested to determine whether the cutting teeth B (Fig. 3) have their points in the proper arc of a circle by applying the device thereto so that the referred to teeth points will contact with the concave face of the blade 11. If but several of the teeth are discovered to be too long

they would desirably be individually cut down to proper length by means of a file held in the hands of the operator. Should there be a number of cutting teeth seen by a 5 comparison with the gage blade 11 to be short, then the saw should be jointed or dressed down to cause the teeth points to be in a common arc.

This operation is performed by employing 10 a file A secured in place and deflected by the clamping screw 12 against the blade 11 whereupon the device is drawn lengthwise over the saw teeth while the ribs 9 are held against a side of the saw blade.

15 The device is then placed upon the saw so that one of its raker teeth, as C (Fig. 3) will project through the slot 19 of the block 16, while the adjacent cutter teeth B support the device by having the plates 14 rest upon these teeth. During the operation, the 20 device is held upright by the operator through the medium of the blade-edge 11¹ and the ribs 8 contacting with the saw blade. Should the points of a raker tooth 25 protrude much above the block surface 16², they are first swaged down to extend but a short distance thereabove and are then filed in the usual manner to dress the points down flush with the block surface and bring the 30 points to acute angles and also afford the requisite hook to the raker-tooth points.

Finally the cutting teeth are individually filed in the ordinary manner of sharpening.

35 After these points are swaged and filed, the ends of the same may be tested as to their being rectangular in a horizontal direction and with respect to the saw blade by bringing an end 19¹ of the slot 19 against a tooth.

40 Among the advantages provided by the present invention, is the means for regulating the plate 11 so that the latter may be curved without being twisted or warped laterally. This function is accomplished by 45 offsetting the stirrup which supports the plate and locating the adjusting screws therefor in the longitudinal axis of the plate.

Another advantage is in the manner or 50 means of connecting the adjacent ends of the plates 14 directly to the frame by screws 15 to afford a fixed and rigid support for these plates instead of clamping the same be-

tween the frame flanges 6 and the block 16, as hitherto, whereby the use of filling or 55 shim pieces between the block and plates 14 is obviated.

The block 16 is in the present invention 60 regulated by loosening the connection therewith of the screws 17 and thereupon regulating the position of the block by means of screws 18, after which the block is secured in its adjusted position to the frame by the screws 17.

What I claim is—

1. In a tool of the class described, a frame 65 having upright web members and flanges extending horizontally from the upper ends of said web members, flexible plates positioned below said flanges and fixedly secured 70 at their inner ends to said flanges, screws extending through threaded holes in the frame flanges for regulating the curvature of said plates, a gage block, adjustment screws extending through threaded holes in 75 said frame flanges for regulating the elevation of said gage block relatively to said plates, screws extending through slots provided in the block and engaging threaded 80 holes in one of said web members for securing the block in adjusted positions to the frame.

2. In a tool of the class described, the combination with a frame having horizontally disposed flanges at the top, and web 85 members extending downwardly from said flanges at the center and in proximity to the frame ends, said web members having their lower portions curved toward the front and terminating in stirrup elements directed to 90 toward the front of the frame, of a plate seated upon and rigidly secured to the central one of said stirrups, adjustment screws extending upwardly through threaded holes provided in the end stirrups and disposed in 95 the longitudinal axis of said plate for supporting the plate adjacent to its ends and regulating its curvature, and a clamping screw co-operating with said plate for bending a file against the latter. 100

Signed at Doty, Washington, this 17th day of March, 1919.

FRANK KNIZEK.
